In Czechoslovakia May 8, 1947

11 Claims. (Cl. 66—110)

1.

The present invention relates to cotton knitting machines and more particularly to a device provided on a cotton knitting machine for deflecting the slurcams in a direction at right angles to the path of the sinking movement of the said slurcams along their stationary guide bar.

In some modern cotton knitting machines it is the practice when knitting a narrowed part of a fabric as is the case, for instance, when knitting the instep of a stocking, to shorten the path of the slurcams, the decrease in length of the slurcam path being utilised to permit a lower speed of the sinking movement of the slurcams so as to increase the reliability and the cleanliness of plating in the knitted fabric. The reduction in length of the slurcam path may be provided for in a number of ways, but in any case it is always necessary for the slurcams to travel to a certain distance beyond the anticipated knitting width of the sinkers. As a consequence it is necessary to provide for deflection of the slurcam out of reach of the jacks of those sinkers which should remain idle, as otherwise such sinkers would interfere with the operation of the sinker box during the actuation of the sinkers and with the operation of the wide and narrow loop transfer combs during their common advance along the needle row.

Several methods are known (e. g., German Patent No. 593,777) permitting to deflect the slurcams out of reach of the jacks of those sinkers which should not be in operation at the completion of the shortened slurcam path. Among the known methods a single one is characterized by an arrangement on a stationary guide bar. In this arrangement the slurcams are mounted in the slurcam housings in such a way as to be movable in a direction at right angles to the direction of movement of the slurcam housing along the stationary guide bar, the slurcams being pulled by spring tension out of reach of the sinker jacks. The locking of the slurcams in a position for controlling the jacks during the time of useful operation of the slurcams is provided for by a movable member working against spring pressure. The disadvantage of the arrangement just described consists in this that before each sinking movement of the slurcams is terminated, presuming that the slurcams are to be removed from the path of the jacks of the idle sinkers, it is always necessary to impart again an impulse to the movable member so that

the latter may unlock the slurcams and allow the springs to deflect the slurcams out of reach of the said jacks. When a new sinking stroke of the slurcams is initiated, the slurcams should be advanced again into the path of the jacks and locked in this position. Therefore, the operation of the movable member requires an independent driving device so that the complete driving arrangement of the machine becomes complicated.

One object of the present invention is to simplify the driving arrangement for the deflecting movement of the slurcams in such a way that it is no longer necessary to shift all the slurcam deflecting members at the end of each sinking movement of the slurcams.

The essential feature of the present invention consists in the arrangement, at the points of reversal of the slurcam movement, of retractable deflecting cams, which in the working position of the same cause the slurcams to be deflected out of reach of the jacks associated with the sinkers. The deflecting cams are adapted to be brought in the path of movement of the slurcams by means of a mechanism which gives to the sinker mechanism an impulse for changing the speed and the length of the path of the slurcams. Therefore, during the entire period of knitting a narrow part of the knitted product the retractable deflecting cams are retained in working position in the path of the slurcams and do not require any special driving devices. Thus, as a whole, the control of the said cams consists in this that at the beginning of the knitting operation on a reduced width of the fabric, when it is desired to reduce at the same time the length of the slurcam path and the speed of the slurcams, the deflecting cams are brought into the path of the slurcam under the action of the same elements which cause the slurcam path to be shortened and its speed to be decreased. The deflecting cams are retained in this position up to the moment when the control device of the slurcams will impart to the latter again their normal length and speed of travel, the deflecting cams being retracted from the path of the slurcams at this exact moment. Preferably the deflecting cams are mounted in the guide bar of the slurcams which during their operation on the sinkers are still held in their normal position by means of a safety detent.

Further advantages and features of the present invention will appear from the following

description when read in conjunction with the accompanying drawings, in which:

Fig. 1 shows the control mechanism of the deflecting cams,

Fig. 2 is a plan view showing one of the deflecting cams in position in the slurcam path; and

Fig. 3 is a sectional side view corresponding to Fig. 1.

Referring more particularly to Figs. 2 and 3, the slurcams 1 are mounted slidably in the slurcam housings 2 which are guided on a stationary bar 3. A spring 4 bearing with its one end against a rib 5 provided on the box 2, and with its other end against the body of the slurcam 1, urges said slurcam 1 permanently in the direction marked in Fig. 2 by the arrow S₁, i. e. toward a position in which the slurcam 1 engages with the sinker jacks (not shown). On the lower part of the body of slurcam 1 is fastened a roller 6 which is guided in a groove 7 formed in the guide bar 3.

At the end positions of the shortened path of the slurcams 1 as provided for in the co-pending application of Jaroslav Vaclavik, Ser. No. 25,606, filed May 7, 1948, and now Patent No. 2,571,314, the groove 7 of the guide bar is provided with a slot 8 through which retractable deflecting cams 9 provided with inclined cam surfaces project, as may be seen in Figs. 1 and 2. At the places of operation of the deflecting cams 9 the groove 7 is provided with a corresponding recess 11. The deflecting cams 9 are moved through the slot 8 up and down in such a way that they are brought into the path of the roller 6 on the slurcam 1 in the groove 7, or are retracted into the said slot 8. Each deflecting cam 9 is provided with a stud 12 (Figs. 1 and 3) which is guided vertically in a bracket 13 fastened to the underside of the guide bar 3. The stud 12 may be shifted by a forked lever 14 which is fastened adjustably on a shaft 15 extending underneath the guide bar 3 and serving to drive all the deflecting cams 9 of the whole machine at the same time. The cam 9 is locked in its upper and lower positions by means of spring urged balls 16, as shown in Fig. 1, engaging into cavities 17 provided in the stud 12. The shaft 15 is controlled from projections 18 provided on the slide of the Coulier mechanism of the type shown in the co-pending application Ser. No. 25,606, the necessary impulse being given by a control shaft 20 which is rotated, for instance, by a pattern drum, not shown, which controls also the Coulier mechanism determining the length of the slurcam path. The shaft 20 drives by means of a lever 21, a link 22 and a lever 23 a shaft 24 which is mounted in bearing 25 arranged in the frame of the machine and carries on its one end a fork 26 engaging between two rings 27 provided on a shaft 28. The rings 27 are keyed on the shaft 28 and are controlled by the fork 26 in such a way as to impart axial motion to the shaft 28, while permitting at the same time turning movement of the said shaft 28. The shaft 28 carries at its one end a lever 29 which through the intermediary of a link 30 and a lever 31 is adapted to rotate the shaft 15, while the opposite end of the shaft 28 carries two cam sectors 32 and 33 keyed on the shaft side by side. By axial movement of the shaft 28 either cam sector may be brought in the path of the projection 18 on the slide 19. The cam sectors 32 and 33 are locked in position by means of spring pressed pins 34 and 35 which are mounted

in housings 36 on the frame of the machine and engage in notches 37 and 38 of the sectors 32 and 33.

During the time when the slurcams control the sinker jacks, the body of each slurcam 1 may be locked in working position in the slurcam housing 2 by means of a detent 39 shown in Fig 3 and engaging in a recess 40 provided in the slurcam body. The detent 39 is rotatable about a pin 41 in the slurcam housing 2 and has an arm 42 co-operating with a stud 43 slideable in the slurcam housing. The detent 39 is forced into the recess 40 by means of a spring 44. During the movement of the slurcam housing 2 the detent 39 is retracted from the recess 40 by contact of the stud 43 with the inclined face 45 of a small arm 46 shown in Fig. 2 and mounted rotatably about a pin 47 in a recess 48 of the bar 3. The spring 49 urges the arm 46 permanently toward the recess 48 out of the way of the stud 43, as shown in dotted lines in Fig. 2. The arm is brought into the path of stud 43 concurrently with the advancing movement of the deflecting cam 9 from the slot 7 into the path of the roller 6 on the body of the slurcam 1, this being effected by means of a cam finger 50 arranged directly on the deflecting cam 9.

The apparatus so far described operates as follows:

When a knitted fabric of normal width is being produced the bodies of the slurcams 1 occupy their normal projected position in which the slurcams act on the jacks, not shown, of the sinkers. Thus the slurcam bodies are in the position shown in Figs. 2 and 3 relatively to the slurcam housing 2. In this position each slurcam body is locked by the detent 39 engaging in the recess 40 of the slurcam body and subjected to the action of the spring 44. Each deflecting cam 9 is in its lower position together with the finger 50 (Fig. 3), so that the slurcam housing 2 when moving sideways along the bar 3 travels beyond the slot 8 to its one end position without the roller 6 being influenced by the cam 9, or the stud 43 by the finger 50. Also the mechanism controlling the deflecting cams 9 is in its starting position shown in Fig. 1, in which the pin 35 engages in the notch 38 of the cam sector 33 which is in position over the projection 18 of the slide 19.

When a narrowed part of the fabric is to be knitted and accordingly the slurcams will be caused to travel along a shortened path at a reduced speed through the intermediary of the Coulier mechanism, not shown, and of a worm drive as shown in co-pending application Ser. No. 25,606, Vaclavik, the commanding shaft will be rotated under the action of the change-over device in the direction of the arrow S₂ shown in Fig. 1, the link 22 will be moved up causing the shaft 24 to turn in the direction of the arrow S₃, and the shaft 24 by means of the fork 26 will cause the shaft 28 to be shifted in the direction of the arrow S₄ to a position in which the cam sector 33 is disengaged from the pin 35 and the cam sector 32 is located over the projection 18 on the slide 19. As a consequence, at the next stroke of the slide 19 to the right, the projection 18 will abut against the cam sector 32 and will cause the same to rotate in the direction of the arrow S₅ to a position in which the pin 34 will engage into the notch 37. Concurrently with the rotation of the sector 32, the shaft 28 is rotated in the same sense together with the lever 29 which through the intermediary of the link 30 and lever 31 will cause the shaft 15 to rotate in the direc-

tion of the arrow S_6 resulting in an upward movement of the deflecting cam 9 , so that the latter enters into the groove 7 of the guide bar 3 , being locked in this position by the ball 16 engaging in the lower cavity 17 of the stud 12 . Concurrently with the upward movement of the deflecting cam 9 , the cam finger 50 is also moved upwards and pushes the arm 46 against the pressure of the spring 49 to the position shown in Fig. 2. At the next stroke of the slurcam housings 2 along the guide bar 3 to the left, first each stud 43 will engage with the inclined face 45 on the arm 46 and by the effect of this inclined face will cause the detent 39 to turn about the pin 41 against the pressure of the spring 44 in such a way that the detent 39 will be disengaged from the recess 40 so that at the next moment, when the roller 6 on the body of each slurcam 1 will engage with the cam face 10 of the deflecting cam 9 , the body, of each slurcam 1 will be pushed into the slurcam housing 2 against the pressure of the spring 4 in a direction opposite to the arrow S_1 whereby each slurcam 1 is moved to the position shown in dotted lines in Fig. 2 out of reach of the jacks which are associated with the sinkers. At the back stroke of each slurcam housing 2 to the right, each slurcam 1 will occupy, during the travel of the roller 6 along the straight groove 7 , again its original outward position to which it will be locked by the detent 39 at the moment when, due to the movement of the housing 2 to the right, the stud 43 will come out of contact with the arm 46 . Towards the end of the travel of each slurcam housing 2 to its right hand extreme position in the shortened path, each slurcam 1 will abut through the stud 43 and roller 6 against a similarly arranged arm 46 of a deflecting cam 9 , so that the slurcam will be unlocked again in the slurcam housing 2 and will be moved out of reach of the jacks associated with the sinkers.

Thus the slurcams 1 are automatically deflected out of reach of the sinker jacks in the above described way at the end points of the slurcam movement during the whole period of knitting a narrowed part of the product without requiring any separate drive.

As soon as the machine should restart knitting over the entire normal width of the knitted fabric, when the slurcams will have to perform their maximum movement and it will be no longer necessary to deflect them out of reach of the sinker jacks, the control shaft 20 , which in a manner known per se is adapted to extend the path of the slurcams and to increase the speed of the latter through the intermediary of the Coulier mechanism, will be rotated in a direction opposite to that marked by the arrow S_2 in Fig. 1, so that the link 22 will be pulled downward. This movement of the link 22 causes the shaft 28 to be moved axially in a direction opposite to that of the arrow S_4 in Fig. 1, so that the cam sector 32 is disengaged from the pin 34 and the cam sector 33 is brought into the path of the projection 18 provided on the slide 19 . Thus during the movement of the slide 19 to the left, the projection 18 will abut against the sector 33 causing the shaft 28 to be turned clockwise, so that the link 30 will be moved upward, the shaft 15 will be turned clockwise and the levers 14 will retract all deflecting cams 9 downwards whereby the whole mechanism will be brought back to the position shown in Fig. 1. By retracting the cams 9 downwards, the pressure of the cam finger 50 on the arm 46 will be relieved and

the latter will be forced by the spring 49 into the recess 48 provided in the bar 3 . Then each slurcam travels along its complete working path in its outward or projected position shown in Fig. 3 in which the slurcam is locked.

What I claim is:

1. In a flat cotton knitting machine, a guide bar, a slur cam housing reciprocable on said guide bar, a retractable slur cam member carried by said slur cam housing, a pair of spaced deflecting cam members disposed in apertures in said guide bar, a reciprocating member constituting a part of the Coulier mechanism of the machine, and means actuated by said reciprocating member 15 of the Coulier mechanism for advancing said deflecting cams into the path of said slur cam member for retracting the same at the ends of the path of reciprocal movement thereof.
2. In a flat cotton knitting machine including 20 a Coulier mechanism, a guide bar, a reciprocating slur cam housing on said guide bar, a slur cam member carried by the slur cam housing, jacks actuated by the slur cam member and narrowing means for driving said slur cam housing at reduced speed and through a shortened path of movement when knitting a narrowed portion of fabric, the improved construction which comprises means for mounting said slur cam for retraction from a projected position to which it 25 engages and actuates the jacks to a retracted position in which it clears the jacks, spaced deflecting cams mounted in apertures in said guide bar at the ends of the shortened path of movement of the slur cam housing and means actuated by a part of the Coulier mechanism for advancing said deflecting cams into the path of movement of the slur cam member to shift the same to retracted position at the end of its motion in each direction.
3. In a flat cotton knitting machine including 30 a Coulier mechanism, a guide bar, a reciprocating slur cam housing on said guide bar, a slur cam member carried by the slur cam housing, jacks actuated by the slur cam member and narrowing 35 means for driving said slur cam housing at reduced speed and through a shortened path of movement when knitting a narrowed portion of fabric, the improved construction which comprises means for mounting said slur cam for retraction from a projected position in which it engages and actuates the jacks to a retracted position in which it clears the jacks, spaced deflecting cams mounted in apertures in said guide bar at the ends of the shortened path of movement of the slur cam housing, and means for 40 maintaining the deflecting cams in the advanced position during the knitting of the narrowed part of the fabric.
4. In a flat cotton knitting machine including 45 a Coulier mechanism, a guide bar, a reciprocating slur cam housing on the guide bar and narrowing means for driving said slur cam housing at reduced speed and through a shortened path for knitting a narrowed portion of fabric, the improved construction which comprises a retractable slur cam mounted on the slur cam housing, spaced deflecting cams disposed in apertures in the guide bar at the ends of the shortened path of motion of the slur cam housing, and shifting means for projecting said deflecting cams vertically into the path of the slur cam and for retaining the same in the projected position during the knitting of a narrowed part of the fabric.
5. In a flat cotton knitting machine including 50 a Coulier mechanism, a guide bar, a reciprocating

slur cam housing on the guide bar and narrowing means for driving said slur cam housing at reduced speed and through a shortened path for knitting a narrowed portion of fabric, the improved construction which comprises a retractable slur cam mounted on the slur cam housing, spaced deflecting cams disposed in apertures in the guide bar at the ends of the shortened path of motion of the slur cam housing, and shifting means actuated by a moving part of the Coulier mechanism for projecting said deflecting cams vertically into the path of the slur cam concurrently with the actuation of the narrowing means to shorten the reciprocal path of the slur cam housing whereby to retract the slur cam from engagement with the sinker jacks at each end of the reciprocal path thereof during the knitting of a narrowed part of the fabric.

6. A knitting machine according to claim 5, in which the shifting means for projecting the deflecting cams into the path of the slur cam includes a pair of cam sectors and the moving part of the Coulier mechanism is provided with a projection which engages said cam sectors to actuate the shifting means.

7. A knitting machine according to claim 5 in which the shifting means for projecting the deflector cams into the path of the slur cam includes a transmission shaft and link and lever connections between the transmission shaft and the deflecting cams, cam sectors on said transmission shaft and a projection on the moving part of the Coulier mechanism for engaging one of said cam sectors to actuate the transmission shaft.

8. In a knitting machine according to claim 7, a control shaft for the sinker mechanism, connections between said control shaft and said transmission shaft for shifting one of the cam sectors into the path of the projection on the moving part of the Coulier mechanism upon rotation of the control shaft.

9. A knitting machine according to claim 8 in which the cam sectors are spaced on said

transmission shaft and the connection between said control shaft and said transmission shaft shifts the latter axially upon rotation of the control shaft.

10. In a cotton knitting machine including a guide bar and a reciprocating slur cam housing on the guide bar, a retractable slur cam mounted in said slur cam housing shiftable from a projected jack engaging position to a retracted jack disengaging position, a spring for biasing said slur cam to a projected position, a pair of retractable deflecting cams disposed one at each end of the path of motion of the slur cam housing, means for shifting said deflecting cams into the path of said slur cam for retracting the same at the ends of its reciprocal path and means for locking the slur cam against retraction during its passage between said deflecting cams.

11. A cotton knitting machine according to claim 10 in which the locking means comprises a detent carried by the slur cam housing and a detent releasing member is provided adjacent each of the deflecting cams for releasing the detent prior to engagement of the slur cam by the deflecting cams when the latter are shifted into the path of the slur cam.
